UNITED STATES PATENT OFFICE.

WESLEY LINFORD SMITH, OF PITTSBURGH, PENNSYLVANIA.

ASH TRAY OR CONTAINER.

1,071,363.

Specification of Letters Patent. Patented Aug. 26, 1913.

Application filed September 17, 1912. Serial No. 720,825.

To all whom it may concern:

Be it known that I, WESLEY LINFORD SMITH, a resident of Pittsburgh, in the county of Allegheny and State of Pennsylvania, have invented a new and useful Improvement in Ash Trays or Containers, of which the following is a specification.

This invention relates to ash trays or receivers such as are used by smokers to hold ashes and waste ends of cigars, cigarettes, etc.

The object of the invention is to produce a simple, effective, and attractive receiver which normally is tightly closed, which may be readily opened by the mere act of thrusting a cigar or cigarette thereinto and which is self-closing, cleanly, antiseptic and can be readily emptied.

A further object of the invention is to provide a combined ash tray and match safe or holder of simple and improved construction.

The invention comprises the construction and arrangement of parts hereinafter described and claimed.

In the drawings Figure 1 is a perspective view of a device constructed according to my invention; Fig. 2 is a vertical section through the same when in normal or closed position; Fig. 3 is a similar view taken on the line 3-3, Fig. 2, showing the same in open position with a cigar end being inserted thereinto; Fig. 4 is an enlarged detail view of a spring; and Fig. 5 is a detail view of a modified form of the invention.

The ash receiver shown in the drawings comprises a suitable jar or vessel 1 which may be formed of any suitable material, as glass, porcelain or bronze, and preferably translucent or opaque to prevent the contents being seen. The vessel may be of any size, shape or proportions and, as shown, is round with a thick, heavy base 2 to prevent it from tipping over. The top 45 of the receptacle is concave or saucer shaped, as at 3, to receive ashes and form a shelf or resting place for cigars or cigarettes. It is provided with a central opening forming a mouth 4 around which is formed a conical 50 seat 5, the angle of inclination thereof being preferably about 45°, although this may be varied. This seat may be formed in the case of glass or porcelain by its glazed surface or by grinding the same, and in the case of bronze or other metal by turning or other-

wise suitably shaping the same. The receptacle is closed by a member having an enlarged stopper or closure 6, the outer surface of which is conical and formed on the same inclination as that of the seat 5 to closely fit the same, and either glazed, ground or turned, as preferred. The stopper is connected by a reduced spindle 7 to a depending weight 8, shown as of bulbous shape and which may be either integral with the stopper 6 or a separate part connected thereto in any manner. Preferably, however, the material of the closure and weight will be the same. The stopper or closure projects above the upper surface of the receptacle and its peripheral portion forms a lip 9 which overhangs the same around the seat 5, as shown in Fig. 2. The weight 8 holds the stopper or closure 6 to the seat 5 by gravity, and the surfaces of the stopper and seat are so formed as to give a perfectly tight fit and practically seal the receptacle, thereby preventing the light ashes and fumes from escaping.

In use of the receptacle the waste stub or end of a cigar or cigarette is thrust or pushed into the receptacle under the overhanging lip 9, as indicated at A, Fig. 3. The weight 8 tends to retain the stopper or closure in its normal position with the axis of the stopper and weight vertical. The force applied in inserting a cigar, however, lifts the stopper and causes it to ride up on the opposite side of seat 5 and tip it out of the vertical. The displacement thus caused is sufficient to permit the cigar or cigarette to be thrust into the space between the reduced spindle 7 and the seat 5, when, upon being released, the cigar drops into the chamber in the receiver. The fingers being withdrawn, the weight 8 automatically returns the stopper or closure to its normal position to again tightly seal the opening of the receiver. It will thus be observed that a single thrusting movement with one hand opens the receptacle and places the waste cigar or cigarette therein, the receptacle then automatically closing itself. The concave or saucer like shelf 3 forms a convenient resting place for cigars or cigarettes and from which they are not easily jarred or accidentally displaced. Preferably, the inclination of the concave upper surface of the receiver will be such that loose ashes placed thereon will slide by gravity toward

the central mouth 4 so that each time the receiver is opened the shelf 3 will automatically clean itself of ashes deposited thereon.

The receiver is preferably also formed to 5 contain or carry matches, although this is not essential. As shown in Figs. 1 to 3, the stopper or closure 6 is provided with a depression or cavity 11 having undercut walls 12, in which cavity is seated the base 13 of a stand or support for the match box. Said base, at its ends, is provided with yielding spring arms 14, which project from beneath the overhanging walls 12 and engage the sides of the cover 15 of a match 10 box of the usual type for holding safety matches. The stand or support is also provided with up-standing supports 16 suitably secured to the base 13, and which support the drawer 17 elevated above the cover 15 thereof, as shown in Fig. 2. The spring arms 14 are completely hidden within the recess 11 and yieldingly engage the side walls of the cover, and thereby securely hold the same removably in place.

25 It will of course be understood that other means than that shown may be used for supporting a match box on the cover of the receiver.

In Fig. 5 a modified form of the invention 30 is illustrated in which the stopper or closure 6 is provided at its top with an up-standing cup 18, preferably formed integral therewith, and which is hollowed out to provide an interior space 19 for the 35 matches. If desired, the outer surface of the cup 18 may be grooved or roughened, as indicated at 20, to provide a convenient striking surface for igniting the matches.

Preferably, the weight 8 depends some 40 distance below the stopper 6 in order to bring the center of gravity of the weight 8 as low as possible and increase the tendency of the parts to return to normal position and tightly close the receptacle. Also, it 45 will be understood that the largest diameter of the weight 8 is less than the smallest diameter of the mouth 4 to enable the closure to be inserted into or removed from the receptacle.

50 Both closure and receptacle may be given any ornamental shape and may be stamped, impressed or embossed with advertising or other matter.

The entire device is simple, inexpensive 55 and sanitary and may be readily cleaned or flushed by merely removing the stopper and weight.

What I claim is:—

1. A device of the character described, 60 comprising a receptacle provided with an opening forming a mouth, a stopper having its upper portion projecting above said mouth and resting upon the edge of said opening, and a weight secured to said stop- 65 per.

2. A device of the character described, comprising a receptacle provided with an opening forming a mouth, a stopper having its upper portion projecting above said mouth and resting upon the edge of said opening, and a weight secured to said stopper, said stopper being formed to receive and hold a supply of matches. 70

3. A device of the character described, comprising a receptacle provided with an opening forming a mouth, a stopper having its upper portion projecting above said mouth and resting upon the edge of said opening, and a weight secured to said stopper, said stopper being provided with a 75 pocket or cavity arranged to receive and hold a supply of matches. 80

4. A device of the character described, comprising a receptacle provided with an opening forming a mouth, a stopper having its upper portion projecting above said mouth and resting upon the edge of said opening, a weight secured to said stopper, and a match holder secured to said stopper. 85

5. A device of the character described, comprising a receptacle provided with an opening forming a mouth, a stopper fitting said mouth and having a portion projecting thereabove and adapted to be moved by the insertion of an article between said stopper 90 and mouth, and a weight depending from said stopper. 95

6. A device of the character described, comprising a receptacle provided with an opening forming a seat, a stopper having an inclined portion resting on said seat and adapted to be raised by the insertion of an article between said stopper and seat, and a weight depending from said stopper. 100

7. A device of the character described, comprising a receptacle provided with an opening having an inclined edge forming a seat, a stopper having an inclined portion fitting and resting on said seat and projecting above said receptacle, and a weight depending from said stopper and arranged to normally hold the same to its seat. 110

8. A device of the character described, comprising a receptacle provided with an opening having an inclined edge forming a seat, a stopper having an inclined portion fitting and resting on said seat and projecting above said receptacle, a weight depending from said stopper and arranged to normally hold the same to its seat, and a match holder secured to the upper portion of said stopper. 115

9. A device of the character described, comprising a receptacle provided with an opening having an inclined edge forming a seat, a stopper having an inclined portion fitting and resting on said seat and projecting above said receptacle, a weight depending from said stopper and arranged 120 125 130

to normally hold the same to its seat, said stopper being provided with a cavity, and a match holder having a portion projecting into said cavity and secured therein.

- 5 10. A device of the character described, comprising a receptacle provided with an opening having an inclined edge forming a seat, a stopper having an inclined portion fitting and resting on said seat and projecting above said receptacle, a weight depending from said stopper and arranged to normally hold the same to its seat, said

stopper being provided with a cavity having inclined walls, a match holder having a portion projecting into said cavity, and a spring within said cavity and arranged to frictionally engage said match holder to thereby removably hold the same in place.

In testimony whereof, I have hereunto set my hand.

WESLEY LINFORD SMITH.
